C. O. SNYDER

SOUND AMPLIFIER FOR RADIO TRANSMISSION

Filed June 19, 1922

Inventor:
Charles O. Snyder;
By Robert H. Randle,

Attorney

UNITED STATES PATENT OFFICE.

CHARLES O. SNYDER, OF RICHMOND, INDIANA.

SOUND AMPLIFIER FOR RADIOTRANSMISSION.

Application filed June 19, 1922. Serial No. 569,408.

The object of my present invention, broadly speaking, is to provide a new construction for conducting and reflecting sound, the same being simple in character, 5 highly efficient in practice, positive in action, easily operated and controlled, and which can be manufactured and sold at a comparatively low price.

More specifically stated my object is to 10 provide a sound transmitter or reflector, by the employment of which the usual telephone set used on one's head in radio production may be applied in such manner that all persons in a room, or in proximity thereto, may distinctly hear the sounds from the 15 radio apparatus without a telephone set being attached to one's person, and whereby one telephone set will answer for a great number of people.

20 The preferred means for carrying out the principles of my invention in a practical manner is shown in the accompanying drawing, in which— Figure 1 is a view looking downward, showing one portion of the device in central horizontal section, and showing a plan view of the other portions of the construction. Figure 2 is a front elevation of the device. Figure 3 is a central cross section of the device, and Figure 4 25 is a plan view showing a slight modification of the arrangement of the conductor.

Similar indices denote like parts throughout the several views.

In order that the construction, the arrangement, the operation, and the advantages of 35 the invention may be more fully understood and appreciated, I will now take up a detailed description thereof, in which I will set forth the same as fully as I may.

40 Referring now to the drawings in detail: The major portion of the construction comprises the relatively large concave (or concavo-convex) reflector or forwardly flaring body 1, preferably elliptical in shape, that is its horizontal diameter is greater than is its vertical diameter.

Connected with the exterior of the lower 45 side of the reflector or body 1 are the two spaced apart brackets 2 and 3, which provide feet, to afford means for permitting the device to rest securely upon a table A, or other surface, and by which the reflector will be supported in its most effective operative position as shown.

55 Numeral 4 denotes the tubular conductor, whose rear or inner portion is formed flar-

ing, as shown, and whose forward portion merges into one or more branches, as for instance the branches 5 and 6, thereby forming a conduit, as indicated in Fig. 3, through 60 which sound waves may pass unobstructed.

Extending out from lower portion of the conductor 4 are the ears 7 and 8, which are adapted to contact with the lower wall of the inner face of the reflector, to which they 65 are adapted to be secured by means of screws or bolts 9. The under portion of the conductor 4 is cut away on a line even with the lower edge of the reflector 1 to the inner end of the conductor 4, whereby the 70 wall or face of the reflector forms the bottom wall of the conductor, as indicated in Fig. 3.

By this arrangement all or part of the flaring portion of the conductor is located 75 inside the reflector, while the branches 5 and 6 are usually outside the reflector, all substantially as shown in Fig. 1.

Extending around and integral with the branches 5 and 6 are the respective collars 80 10 and 11, thereby forming the end portions of the branches into the respective nipples 12 and 13.

Numerals 14 and 15 denote cushions, each being in the nature of a collar, preferably 85 of rubber, which fit around the respective nipples 12 and 13, and extending slightly therebeyond, with their inner ends in contact with the respective collars 10 and 11, which prevent them slipping inward beyond 90 the distance desired.

Letters B and C denote two receivers of a telephone set, each being provided with its two electric wires D—D' and E—E', respectively, through which electric circuits 95 may be established.

Pivoted to said receivers are the respective stems F and G, and slidably connecting said stems is the spring head-band H.

In the usual practice the band H is placed 100 over the top of one's head, while the spring resiliency of said band causes the faces of the receivers B and C to be pressed firmly against one's ears, whereby a single person only hears the sounds produced in the receivers. However when using my invention the receivers are sprung apart and then their faces are brought into contact with the outer ends of the cushions 14 and 15, where they 105 will be retained by the contraction of the spring head-band, the same as they may be retained in contact with one's ears. And it 110

is to be understood that transmitters may be likewise used when desired.

- In the construction just described, pertaining more particularly to Figs. 1 and 2, 5 the receivers B and C, or transmitters, will be retained in operative position as shown simply by the tension of the spring head band H, as the pressure of one will counterbalance the other. However where the 10 branches 5 and 6 do not extend directly opposite to each other but are disposed at angles with relation to each other, as shown in Fig. 4, then additional means must be provided to retain the receivers on their 15 cushions. This may be accomplished by means of the rubber bands I and J, or other means or devices may be provided. When in place said bands are under tension and afford a ready and effective retaining means. 20 It will now be seen that with the receivers attached, as shown, that the sounds developed in the receivers B and C will pass through the branches 5 and 6 into the conductor 4, and then to one side of the central 25 portion of the interior of the reflector, from

which latter the sound waves will be deflected in such way that any one within a broad radius may hear distinctly.

I desire that it be understood that various changes may be made in the several 30 details of construction herein shown without departing from the spirit of the invention and without sacrificing any of the advantages thereof which are new and useful.

Having now fully shown and described 35 my invention, what I claim and desire to secure by Letters Patent of the United States, is—

A sound amplifier for radio transmission comprising in combination, a concave reflector forming the body of the device, a tubular conductor located inside the reflector with one end of the conductor directed inward toward the vortex of the reflector, the inner portion of the conductor being 40 formed flaring, and the lower portion of the conductor being cut away and forming a bottom therefor, all substantially as set forth.

CHARLES O. SNYDER.
